UNITED STATES PATENT OFFICE.

BRADLEY DOBIE, OF ELMHURST, NEW YORK, ASSIGNOR TO AMERICAN ARCH COMPANY, OF NEW YORK, N. Y., A CORPORATION OF DELAWARE.

IGNITION ARCH.

Application filed February 3, 1923. Serial No. 616,648

This invention relates to furnace structures and particularly to ignition arches, such as are used, for example, in stoker fired furnaces.

- 5 One of the objects of my invention is to provide a sprung ignition arch of such character that ordinary unskilled labor can be employed to effect replacement or repairs.
- 10 Another object of my invention is to provide an improved form of ignition arch of sectional construction permitting of the replacement or renewal of damaged or worn out portions without involving the loss or 15 waste of the sound portions, as has hitherto been the case in arches of the type to which this invention is particularly directed, as will further appear.
- Still another object of my invention is to 20 provide an independent support for the ignition arch with respect to the wall beneath which it is carried; and also the arrangement of the arch supporting means in such manner as to be attachable, detachable and 25 renewable without disturbing such wall.

In general, my invention contemplates the provision of an improved ignition arch which is practical; simple to apply; involves very low maintenance cost; and offers more 30 satisfactory ignition conditions.

The foregoing, together with such other objects as may hereinafter appear, or are incident to my invention, I obtain by means 35 of a construction, the preferred embodiments of which are illustrated in the accompanying drawings, wherein:

Fig. 1 is a fragmentary cross sectional view of a portion of a stoker fired furnace, illustrating the application of my invention thereto; Fig. 2 is a section taken on the line 40 2-2 of Fig. 1; Fig. 3 is an enlarged cross section illustrating details of my invention; and Fig. 4 is a front elevation of portions of Fig. 3.

45 Referring now to Fig. 1, the reference letter A denotes a portion of the combustion chamber, defined in part by the main arch B, the front or curtain wall C and the ignition arch D. The stoker mechanism is diagrammatically indicated at 7, the reference character 8, indicating the firing opening through which the green coal is introduced by the stoker mechanism. The side walls of the combustion chamber are shown 50 at 9 in Fig. 2.

In the practice heretofore employed in ignition arches of this type, the arch was composed of a row of bricks or tile of the required dimension, such bricks being supported by hangers, hooked in a wall supporting channel so as to lie behind the bricks of the front wall. Certain difficulties were incident to this arrangement, one of such difficulties being that if it was desired to renew or replace one of the hangers, the front wall 60 would have to be broken out. Another difficulty was that any inaccuracy in punching of the channels or in the manufacture of the hangers or the bricks would result in difficulty in installing the arch. 70

The bricks or tiles themselves were also of large dimension which involves difficulties in manufacture, shipment, handling and installation, as well as marked spalling in service due to heavy internal stresses. 75

Furthermore, the inner portion of the tile would wear out much more rapidly than the outer portion, but in making repairs the sound portions of the brick would have to be discarded. 80

85 My invention, among other things, is intended to overcome these difficulties and to this end I construct each tile F of split brick, preferably of what may be termed "quarter brick".

Referring now to Figs. 3 and 4, it will be seen that each tile comprises a right and left-handed inner quarter brick 13, and right and left-handed outer quarter brick 14, the upper ends of the quarter brick being formed so as to produce, when assembled, a T-shaped head 15. The course or row of tile is supported by means of suspension hangers 16 engaging the heads 15, for which purpose they are provided with heads 17. 90 Pairs of these suspension hangers 16, which extend transversely of the arch and of the support 19, are carried on supporting devices or brackets 18 secured against the lower face of the front wall supporting structural work 19, that extends along the arch beneath and at the outer side of the wall, and of the arch as well, in the manner illustrated in Figs. 3 and 4. Each bracket 18 is provided with a pair of hooks 20 and a pair of hooks 21, on its depending portion 18' and on its overhead portion, respectively, and each hanger has a hook 20' at its outer end and a hook 21' at its inner upper end, respectively 95 adapted to engage a hook 20 and a hook 21. 105 110

The hangers 16 are thus supported as against displacement in a direction transversely of the arch but they can be assembled or detached on relative movement of translation 5 in a direction, longitudinally of the arch. The hooks on the hangers have rounded faces, as shown, so that they float or rock to permit the tile to expand and contract and to accommodate themselves to the 10 spring of the arch. It will also be seen that the arrangement is such that if for any reason it is desired to remove or replace a hanger, access can be had by removing or breaking out two quarter bricks.

15 The upper edges of the tile, the head 15 and the hangers 16 are inclined so that the tile will be held in position, in which connection the downwardly depending leg 18' of the bracket serves to prevent the bricks 20 from sliding off the hanger.

The gap between the bottom of the front or curtain wall C and the quarter bricks 13 is filled by bricks 22, such bricks being wedge-shaped so that the tile serve to position them.

In so far as the arch supporting mechanism is concerned, it will be seen that this is of such character that the ignition arch is independent of the front wall and can 30 be installed, repaired and replaced without disturbing said wall in any manner, by displacing the inner and outer brick sections 13, 14 in the same direction (inward) sidewise of the supporting means 19 and of the arch 35 and the wall C, while at the same time the supporting means can be inserted and removed and replaced without disturbing the front wall. In addition the metal parts are 40 fully protected against the heat and are exposed toward and accessible from the exterior.

In so far as the arch is concerned, this, it will be seen, is composed of much smaller bricks than heretofore, the split brick being 45 more easy to manufacture, ship and handle, and less liable to spalling because the internal stresses to which they are subjected in service are not nearly so great. The inner

portions of the ignition arch nearest the source of greatest heat deteriorate much 50 more rapidly than the outer portions and by my improvement in dividing the arch into sections transversely, any one or more of the bricks constituting the inner section can be renewed without disturbing the bricks 55 constituting the outer section. This is ordinarily done by breaking out the damaged brick or bricks and sliding new bricks into the spaces left.

With respect to the hanger mechanism, it 60 will be seen that this is of simple character and permits the arch to expand and contract both longitudinally and transversely. One reason why sprung arches have not been widely used, and this is particularly true 65 with respect to ignition arches, is that skilled labor is required to install and maintain such arches, but by my improvements unskilled labor can install and maintain the arch. Side thrust on the side walls is reduced to a negligible factor and the incoming fuel is effectively subjected to radiant heat from the sprung arch.

Other advantages will occur to those skilled in the art.

What I claim is:

1. A supporting system for an ignition arch comprising a longitudinal support, a bracket with a depending portion carried by said support, and tile-engaging means floatingly mounted on said bracket extending and inclined transversely of said supporting means, downward in the direction of said depending portion of said bracket.

2. A supporting system for an ignition 85 arch comprising a longitudinal support, a supporting device carried thereby with a depending portion at one side, and a brick-engaging support extending transversely of said longitudinal support, hooked to the upper portion of said device at one end and to its said depending portion at the other end.

In testimony whereof, I have hereunto signed my name.

BRADLEY DOBIE.
